COLLAPSIBLE TUBE

Frederic Remington, Elizabeth, and Lambert Sigfred Linderoth, Jr., Newark, N. J., assignors to Peerless Tube Company, Bloomfield, N. J., a corporation of New Jersey

Application May 16, 1935, Serial No. 21,870

13 Claims. (Cl. 221—60)

This invention relates to improvements in collapsible tubes, and has to do, more particularly, with the provision of means for sealing the dispensing necks thereof during the period prior to initial use of the tube contents.

As is well known in the general art to which the present invention relates, the conventional threaded cap employed as a closure for collapsible tubes is inadequate in many instances, particularly in cases where the preparation packaged contains volatile ingredients or other substances which are affected by exposure to air. Because of this recognized fact, a large number of such tubes are provided with an inner closure or bore seal consisting of an integral metallic web or diaphragm formed across the bore of the tube neck coincidentally with the manufacture of the tube by extrusion methods. In thus simultaneously forming the inner seal from the material of the tube proper on a commercial scale, it is practically impossible to hold the thickness of the web within narrow limits. As a result, in many instances, such sealing webs are far thicker than necessary or desirable and, because of the toughness of the metals from which such tubes are commonly fabricated, considerable pressure must be applied upon the implement used to effect puncture of the seal and opening of the dispensing bore.

Moreover, the user of products packaged in collapsible tubes of the foregoing pre-sealed type generally employs, as a seal-puncturing implement, whatever means is closest at hand, be it penknife, pin, fork, nail file, or other convenient device. Because of the diversity of puncturing implements employed and their inaptitude for the purpose, as well as the lack of uniformity in the thickness and the toughness of the sealing webs themselves, the user frequently exerts such pressure upon the tube body, in grasping the same during rupture of the seal, as to cause partial loss of tube contents, sometimes so violent as to be characterized by a "squirting" thereof.

Many of the preparations packaged in such presealed tubes are highly active chemically, for example, depilatory creams, rubber cement, and the like. Violent discharge or "squirting" of such substances, particularly into the eyes of the prospective user, is an admitted nuisance, if not a hazard. In addition to the objection to such tubes predicated upon the partial loss of contents during unsealing, it frequently occurs that the tube neck, with its threads, is deformed to such an extent that the cap provided for subsequent

closure is difficult or impossible of reapplication in effective resealing relation.

With these and other objections and disadvantages inherent to this heretofore universally accepted prior art construction, the present invention has for its purpose several well defined objects.

It is, accordingly, a primary object of this invention to provide an hermetically pre-sealed collapsible tube which may be more easily opened for use of its contents than those embodying constructions heretofore known.

It is another object of this invention to provide an hermetically pre-sealed collapsible tube which does not require the employment of a puncturing implement to render the contents of the tube available for use.

It is an object of this invention to provide an hermetically pre-sealed collapsible tube which, while readily openable at will, is secure against loss or deterioration of contents during shipping and storage.

It is an object of this invention to provide an hermetically pre-sealed collapsible tube which, when unsealed for use, is provided with a substantially unrestricted discharge port from which contents of the tube may be dispensed with facility and neatness as contrasted with the "snaky" or otherwise irregular emission characteristic of tubes the necks of which require puncturing with a pointed implement.

It is an object of this invention to provide an hermetically pre-sealed collapsible tube in which the seal-rupturing operation does not necessitate the application of a "strangle-hold" upon the body of the tube and therefore does not occasion unintentional loss of tube contents resulting from inadvertent constriction of the tube body during the opening operation.

It is an object of this invention to provide an hermetically pre-sealed collapsible tube the sealing means of which is ruptured prior to removal of the conventional threaded cap associated therewith, thus positively precluding ejection of contents even in instances where, due to previous deformation of the tube in shipping or expansion of the contents in storage, internal pressure is present and seeks relief during rupture of the seal.

It is an object of this invention to provide hermetic sealing means for collapsible tubes which sealing means is cleanly ruptured affording no disfiguration of the tube neck or interference with the subsequent reapplication of the conventional threaded cap.

55

It is an object of this invention to provide a non-metallic hermetic seal for collapsible tubes which is adequately resistant to the extremes of temperature and humidity experienced in tropical climates.

It is an object of this invention to provide an easily ruptured hermetic pre-seal for conventional screw-threaded collapsible tube necks, which seal serves the supplemental function of so locking the closure cap thereon as to preclude dissociation thereof even by rough handling in shipment.

It is an object of this invention to provide an inexpensive method and means for hermetically presealing the discharge orifices of collapsible tubes, which method and means are universally applicable and effective for the packaging of substantially all plastic preparations regardless of their chemical composition.

Further objects, and objects relating to details and economies of manufacture and use will definitely appear from the detailed description to follow. In one instance, we accomplish the objects of our invention by the methods and means set forth in the following specification. Our invention is clearly defined in the appended claims. Structures constituting preferred embodiments of our invention are illustrated in the accompanying drawings forming a part of this specification, in which:

Figure 1 is a vertical sectional view, on a reduced scale, diagrammatically illustrating a plurality of collapsible tubes with assembled threaded caps of conventional design mounted in apparatus for applying to the dispensing neck of each of said tubes, an hermetic seal constituting a preferred embodiment of this invention;

Fig. 2 is a detailed sectional view of the neck portion of one of said collapsible tubes, showing the seal-applying spindle bearing a drop of sealing material and about to deposit said sealing material upon the inner surface of the tube closure;

Fig. 3 is a similar detailed sectional view showing the sealing material after it has spread, by surface tension, into wetting and sealing relation with the walls of the dispensing opening of the tube, the seal-applying spindle having been elevated and removed from the tube;

Fig. 4 is a detailed sectional view of the type of collapsible tube closure illustrated in the previous figures and found to be most suitable for use with the sealing means and method constituting a preferred embodiment of this invention;

Fig. 5 is a detail view, in elevation, of the closure member, showing the inside faces thereof;

Fig. 6 is a view, in side elevation, of another form of apparatus adapted for the application of a seal constituting a preferred embodiment of this invention, the neck and cap portions of the collapsible tube mounted upon the seal-applying mandrel of said apparatus being shown in section;

Fig. 7 is a detailed sectional view of the tip end of the seal-applying mandrel constituting a portion of the apparatus illustrated in Fig. 6;

Fig. 8 is a perspective view of the tip end of the mandrel illustrated in Fig. 7;

Fig. 9 is a vertical sectional view of a collapsible tube and cap closure provided with an hermetic seal constituting a preferred embodiment of this invention, said tube having been filled with contents to be packaged and being in condition

for crimping and closure of its filling and; and

Fig. 10 is a vertical sectional view similar to Fig. 3, but on a reduced scale, said view illustrating another form of sealing member resulting from practice of our invention and constituting a slightly modified embodiment thereof.

In the application drawings, Figures 1 and 6 are drawn to reduced scale; Fig. 9 is drawn on an enlarged scale of approximately 2:1 and Figs. 2, 3, and 4 are greatly enlarged to more clearly illustrate the form of the seal.

Like numerals of reference refer to like parts throughout the several views.

In a broad aspect, this invention consists in the substitution, for the integral metallic sealing web commonly employed in collapsible tubes, of a sealing film or membrane of initially fluid or plastic material, which sealing member is adhesively bonded to the adjacent surfaces of the dispensing neck of the tube and the closure assembled therewith, said sealing member being formed of a substance or composition which is non-solvent and inert in the contents to be packaged in the thus sealed tube. In a narrow sense, the sealing member is applied in a fluid or plastic condition and is of a nature such that, before filling of the tube with the contents to be packaged, a setting of the seal takes place such that the seal is brittle or frangible in nature and is easily ruptured upon removal or rotation of the closure member with respect to the neck of the tube. The expression "pre-sealing", as employed in this specification, refers to the provision of the herein-described hermetic seal between the adjacent faces of the tube neck and the closure cap assembled therewith, at a time prior to the conventional filling of the tube through its butt end and the closure of said butt end by crimping.

More specifically, and with reference to the accompanying drawings in which is illustrated a preferred form of the present invention, Fig. 3 discloses the dispensing neck portion 11 of a conventional collapsible tube (shown in part) which neck 11 is provided with an external thread 12 upon which is assembled a cap member 13 having internal threads 14 complementary to the thread 12 of the tube neck. The cap member also includes a flange portion 15, preferably of knurled form to facilitate gripping thereof by the fingers, and a central internal tapered plug portion 16 which extends into the bore of the dispensing neck 11 of the tube and is seated therein, defining therewith an annular groove 17 of V-shape inward of the line of contact of the plug portion 16 with the tube neck. Filling the annular groove 17, and bonded to the portions of the plug element 16 and the neck 11 which define said annular groove 17, is a sealing element 18. The sealing element 18 is formed in situ upon the annular groove defining surfaces of the cap and neck member by applying, to the cap member as indicated in Fig. 2, a drop of fluid or plastic material which has the characteristic of wetting the material of the plug portion 16 and spreading thereon, by surface tension, into adhesive wetting contact with the adjacent surfaces of the tube neck 11. Preferably, the material employed for forming the seal 18 is applied by a spindle member 19 having a reduced tip portion 20 to which a drop or globule of sealing material delicately adheres and by which such a quantity of sealing material may be transferred, from a vessel containing a quan-

tity thereof, to the inner surface of the cap member with measured uniformity.

In particular, and with reference to Fig. 1 of the drawings, a plurality of open-ended collapsible tubes are assembled with cap members of the type illustrated in Figs. 4 and 5 and are mounted, caps down, in a supporting member or tray 21 provided with a plurality of tube-receiving sockets 22. Sealing material is delivered 10 into the bank of tubes thus supported in the tray 21 by a series of appropriately spaced spindle members 19 carried by an arm 23. A supply of sealing material in a fluid state is maintained at a fixed level in the trough 24 by a 15 hydrostatic feeding reservoir 25 of the type commonly employed for the maintenance of fluids in such devices as drinking fountains for poultry. By means of a suitable mechanism (not shown) the arm 23 is periodically actuated to 20 immerse the tips 20 of the bank of spindles 19 in the supply of sealing material maintained in the trough 24, causing equal quantities of sealing material to be withdrawn upon the ends 25 of the spindles and thence to be carried into the bank of tubes in the support 21 and transferred to the inner surfaces of the several cap members 15. The spindles, after transfer of their drop-like quantities of sealing material upon the respective caps, are withdrawn from 30 the tubes thus operated upon, and the deposited quantities of sealing material spread over the respective surfaces of the plug portions 16 as described, assuming the form illustrated in Fig. 3. The operation just described is cyclic, a new 35 bank of tubes maintained in inverted position by another tray 21, or another series of sockets 22 in the same tray, being moved into position during the return of the spindles to the supply trough 24. The bank of tubes which have been operated upon is removed, either automatically 40 or by an operator, and replaced by a new set of as yet un-processed tubes during the application of sealing material to the succeeding bank and, upon completion of the operation upon the successive bank mentioned, the substituted bank 45 of tubes is processed, thus providing continuous operation.

Because of the minute quantities of material employed for the formation of the seals in each bank, a single charging of the reservoir 25 will suffice for the processing of a large number of tubes. While the spindle 19 has been illustrated as applying the droplet of sealing material to the center portion of the plug 16 of each tube of the bank, it is obvious that the sealing material 50 may be applied eccentrically by appropriate displacement of the spindles 19. The disk-like sealing member illustrated in Fig. 3 results from the central application of the drop of sealing material. It is obvious, however, that by eccentrically applying a droplet of material, and employing a substance of relatively high viscosity or of a lesser quantity, the sealing member 18a thus formed will be annular rather than disk-like and will fill only the groove 17. Such a construction is illustrated in Fig. 10 and will suffice in most instances, particularly where the nature of the contents to be packaged is such that actual contact thereof with the material of the cap, and over a long period, will not result in deleterious effects upon either the cap or the contents. Such caps are, in commercial practice, formed of plastic materials which have fair resistance to strongly basic materials. In 65 some instances, however, as where highly alka-

line contents are to be packaged, it is desirable to employ a sealing member of disk-like form such as illustrated in Fig. 3, in order to prevent injury to the cap and to its purely mechanical sealing surfaces upon which reliance must be placed after the initial seal has been broken, i. e., during the period of consumption of the tube contents.

In Fig. 6 is illustrated an alternative form of apparatus for the in situ fabrication of an 10 hermetic sealing member embodying our invention. In this apparatus each collapsible tube, prior to filling, is mounted upon a revolving mandrel 26 having an axial passage or duct 27 therein which extends into the dispensing bore 15 of the mounted collapsible tube and terminates in close proximity with the inner surface of the plug portion 16 of the closure 13. The mandrel, with its assembled collapsible tube, is rotated, at slow speed, by conventional means (not 20 shown) such as are employed, in this art, for rotating mandrels forming part of coating, printing or trimming machines. If desired, these operations, or any of them, may be executed by a suitable in-building of the present apparatus 25 with such machines. A reservoir 28 is employed for containing a suitable quantity of fluid seal-forming material, and feeding thereof in minute quantity to the cap face is effected through the operation of the valve 29 in the feed line 30 30 coupled to the duct 27 of the mandrel by a suitable stuffing box 31. The valve 29 is provided with linkage 32 which is driven in timed relation with the mandrel 26, or with mechanism (not shown) for automatically placing 35 and removing tubes therefrom, which linkage provides a nice actuation of the valve such as necessary to effect deposit of a drop-like quantity of sealing material on the inner surfaces of each successive tube and cap. In the case of 40 air-setting sealing compositions, each collapsible tube as treated, is removed from the horizontally disposed mandrel 26 and placed upright, cap down, in a suitable stand during which subsequent period spreading and final setting takes 45 place. Various expedients such as heating or forced air contact may be availed of to expedite setting of the seals.

Collapsible tubes, thus provided with neck seals, are ready for filling in the conventional 50 manner illustrated in Fig. 9, the packaged contents 33 being placed in direct contact with the sealing member 18 by the filling nozzle 34. After filling, the charging end 10a of the tube is closed and sealed in the conventional manner.

For many purposes, particularly in instances 55 where the contents to be packaged are relatively neutral or acidic in reaction, synthetic resinous sealing materials of the phenol-formaldehyde-condensations type have been found highly satisfactory. Such compositions, in a varnish-like form, are readily obtainable at low cost and provide hard, adherent films which are sufficiently brittle or frangible to serve admirably for the present purpose.

Where the contents to be packaged are strongly 60 alkaline, as in the case of depilatory creams containing calcium sulfhydrate, special resinous materials of alkaline-resistant nature are similarly available. Natural resins are suitable 65 for many purposes, and in some instances paraffin and lower-melting petroleum derivatives are advantageously adaptable because of their inert nature and non-solvent character in aqueous colloidal preparations. Other sealing materials 70 75

will appear to those skilled in the art as suitable or preferable for the practice of this invention in providing a seal for collapsible tubes for the packaging of special compositions.

5 Preferably, though not by way of limitation, in employing setting materials for the seal formation, care should be taken to prevent access of the sealing material to the threads of the cap and tube neck. Where such sealing materials 10 are of a searching nature and gain access to the threads, for example by reason of inadequate seating of the plug portion 16 in the bore of the neck, the cap may become so firmly locked to the neck as to require excessive effort to 15 effect dissociation thereof and rupture of the sealing member 17. Numerous structural variations of the illustrated form of the invention, for example modification of the cross sectional shape of the dispensing bore to provide ribbon-like or other shapes of the contents as dispensed, are contemplated. We, therefore, claim our invention broadly as indicated by the appended claims.

What is claimed is:

25 1. A collapsible tube having a neck provided with a bore for dispensing contents packaged in said tube, a detachable closure associated with said neck and closing said bore, and hermetic sealing means for pre-sealing said neck and closure and automatically rupturable upon initial removal of said closure, said sealing means comprising a thin film of material adhesively bonded to the inner face of said closure and the walls of said bore and non-solvent in the contents 30 packaged in said tube.

2. A collapsible tube having a neck provided with a bore for dispensing contents packaged in said tube, a detachable closure associated with said neck and closing said bore, and hermetic 35 sealing means for pre-sealing said neck and closure and automatically rupturable upon initial removal of said closure, said sealing means comprising a thin membrane-like film of non-metallic material adhesively bonded to the inner face 40 of said closure and the walls of said bore and non-solvent in the contents packaged in said tube.

3. A collapsible tube having a threaded neck provided with a bore for dispensing contents 50 packaged in said tube, a threaded cap seated upon said neck and closing said bore, and hermetic sealing means for pre-sealing said neck and closure automatically rupturable upon unthreading of said cap, said sealing means comprising a thin film of material adhesively bonded to the inner face of said cap and the walls of 55 said bore and non-solvent in the contents packaged in said tube.

4. A collapsible tube having a threaded neck 60 provided with a bore for dispensing contents packaged in said tube, a threaded cap seated upon said neck and closing said bore, and hermetic sealing means for presealing said neck and closure automatically rupturable upon unthreading of said cap, said sealing means comprising a thin membrane-like film of non-metallic material adhesively bonded to the inner face 65 of said cap and the walls of said bore and non-solvent in the contents packaged in said tube.

70 5. A collapsible tube having a threaded neck provided with a bore for dispensing contents 75 packaged in said tube, a threaded cap associated with said tube neck and closing said tube neck and closing said bore, and means for initially hermetically sealing said neck and closure and

securing said cap against inadvertent dissociation from said neck, said last-recited means comprising a thin film of solidified plastic material adhesively bonded to the inner face of said cap and the walls of said bore, said solidified sealing material having the characteristic of being inert to, and non-solvent in, the contents packaged in said tube and having such resistance to fracture as to preclude loosening of said cap in the absence of the application of positive 10 rotative effort thereto.

6. A collapsible tube having an externally threaded neck provided with a central bore for dispensing contents packaged in said tube, a cap member having an internally threaded portion 15 engageable with the threads of said tube neck and an internal plug-like portion receivable within the bore of said neck when said cap is assembled therewith, and means for hermetically pre-sealing said plug portion in said bore, 20 said last-recited means comprising a thin film of material adhesively bonded to said plug portion and the walls of said bore and having the characteristic of being non-solvent in the contents packaged in said tube.

25 7. A collapsible tube having an externally threaded neck provided with a central bore for dispensing contents packaged in said tube, a cap member having an internally threaded portion engageable with the threads of said tube neck and an internal plug-like portion receivable within the bore of said neck when said cap is assembled therewith, and means for hermetically presealing said plug portion in said bore, said last-recited means comprising a film-like annulus of material adhesively bonded to said plug portion and the walls of said bore and having the characteristic of being non-solvent in the contents packaged in said tube.

35 8. A collapsible tube having an externally threaded neck provided with a cylindrical bore for dispensing contents packaged in said tube, a cap member having an internally threaded portion engageable with the threads of said tube neck and an internal plug-like portion of tapered 40 form seatable in said cylindrical bore and defining therewith, a groove-like annular space, and means for hermetically pre-sealing said plug portion in said bore, said last-recited means comprising a thin annular film of adhesive material 45 disposed in said groove-like annular space, said annular film of material having the characteristic of being non-solvent in the contents packaged in said tube.

50 9. A collapsible tube having an externally threaded neck provided with a cylindrical bore for dispensing contents packaged in said tube, a cap member having an internally threaded portion engageable with the threads of said tube neck and an internal plug-like portion of tapered 55 form seatable in said cylindrical bore and defining therewith, a groove-like annular space, and means for hermetically pre-sealing said plug portion in said bore, said last-recited means comprising a thin annular film of solidified plastic cementitious material disposed in said groove-like 60 annular space, said annular film of material having the characteristic of being non-solvent in the contents packaged in said tube.

65 10. A collapsible tube having a neck provided with a bore for dispensing contents packaged in said tube, a plug-like closure member disposed in said bore, and means for hermetically sealing said plug-like member in said bore, said sealing means comprising a thin film of plastic adhesive 70

material chemically inert to the contents of said tube and non-solvent therein, said film being rupturable upon removal of said plug in the bore of said neck.

- 5 11. A collapsible tube having a neck provided with a bore for dispensing contents packaged in said tube, a plug-like closure member disposed in said bore, and means for hermetically sealing said plug-like member in said bore and preventing unintentional dissociation thereof from said tube neck, said last-recited means comprising a solidified film of initially fluid adhesive material rupturable upon removal or rotation of said plug with respect to said neck.
- 10 12. A collapsible tube having a reduced neck provided with a bore for dispensing contents packaged in said tube, a detachable cap element on said tube neck, and means for hermetically pre-sealing said dispensing neck and retaining

said cap thereon, said means comprising a thin annular film of initially plastic adhesive material in sealing contact with the inner surface of said cap and said tube neck.

13. A shipping and dispensing container for plastic acidic materials comprising a collapsible tube terminating at one end in a thickened neck portion provided with a central dispensing bore, a cap member detachably secured to the end of said tube neck, closing said bore, and a thin brittle film of synthetic resinous material adhesively bonded to the inner surface of said cap and said neck, hermetically sealing said parts, said resinous material being of an acid-resistant character insoluble in the contents to be packaged.
